ELECTRICAL PLUG RECEPTACLE FOR
REMOTE CONTROL OF LOADS

Joseph M. Harcharek, Upper Darby, Pa.

Application December 31, 1948, Serial No. 68,595

3 Claims. (Cl. 173—334)

1

This invention relates to electrical plug receptacles, and more particularly to a plug receptacle providing means for connecting a switch or other device in series with a load, so that the load may be remotely controlled.

A main object of the invention is to provide a novel and improved plug receptacle enabling switches or other control devices to be inserted in series with a load device without breaking the line cord wires leading to the load device, whereby said load device may be conveniently controlled from one or more points remote therefrom.

A further object of the invention is to provide an improved plug connector device which can be included in an electrical circuit to establish remote control circuits for a load without the use of tools and in a simple manner, said connector device including means for establishing connections with loads additional to that being remotely controlled.

Further objects and advantages of the invention will become apparent from the following description and claims, and from the accompanying drawings, wherein:

Figure 1 is a vertical cross-sectional view, taken on line 1—1 of Figure 2, showing the internal details of a plug receptacle device constructed in accordance with the present invention.

Figure 2 is a vertical cross-sectional view taken through the device of Figure 1, on line 2—2 of Figure 1.

Figure 3 is an elevational view of a plug which fits into the receptacle openings of the device shown in Figures 1 and 2.

Figure 4 is a bottom plan view of the plug illustrated in Figure 3.

Figure 5 is a combined perspective view and schematic diagram showing how the electrical conductors of the structure shown in Figures 1 to 4 are connected into an electrical load circuit.

Figure 6 is a view showing the pre-engaging relationship between the plug receptacle device of Figures 1 and 2, a multiplicity of plugs such as shown in Figures 3 and 4, and a wall receptacle.

Figure 7 is a combined perspective view and schematic diagram similar to Figure 5 but employing a modified form of plug receptacle device in accordance with the present invention.

Figure 8 is a view similar to Figure 6 but showing a still further modified form of the present invention.

Figure 9 is a view similar to Figure 6 but showing how the plug receptacle of either Figure 1 or Figure 7 may be employed with a screw-type socket.

2

Referring to the drawings, numerals 11 and 12 designate metallic prong conductors of standard size and spacing for engaging into electrical connection with commonly used wall plug receptacles, such as is designated by numeral 13 of Figure 6. Designated at 14 is a metallic bar conductor extending at right angles to prong 11, mechanically and electrically connected thereto by any suitable rigid securing means such as rivets, welds, or bracing. Designated at 16 is a metallic bar conductor extending parallel to and spaced from bar conductor 14. Conductor 16 is connected to prong 12 by means of a strap bar 15 bridging bar 14, as shown in Figure 2. Connected to and depending from bar 16 is a hooked spring female contact bar 17. The adjacent ends of bars 14 and 16 are also formed to define spring contact elements having the same standard spacing as prongs 11 and 12, whereby they may be employed as female contact elements for standard electric plugs, as will be subsequently described.

Designated at 18 is a female contact bar located adjacent to one end of bar 16 on the side opposite to bar 14. Secured to bar 18 and extending at right angles thereto is a female contact bar 19 extending parallel to bar 17 on one side thereof. Designated at 21 is a female contact bar located adjacent the other end of bar 16. Secured to bar 21 and extending at right angles thereto is a female contact bar 20 extending parallel to bar 17 on the side opposite to bar 19. Thus there is defined three female contact systems each being engageable by the prongs of a plug such as is shown in Figures 3 and 4 at 30, said plug having the prongs 22, 23 and 24. The prongs 22, 23 and 24 may engage the respective female contact elements 17, 19 and 20 or the respective female contact elements at the two opposite lateral sides of the plug receptacle device.

The conductors shown in Figures 1 and 2 are supported mechanically and are simultaneously insulated electrically from each other wherever necessary by body members, shown at 25 and 26 of suitable insulating material such as plastic, ceramic, or the like, said body members being held together by suitable means such as bolts 27 and nuts 28. The body members are formed with suitable grooves or recesses for receiving the pre-assembled conductors prior to the assembly of the aforesaid body members, said recesses defining wall apertures adjacent the respective female contact elements wherein the prongs of the plugs 30 may be received. If so desired, the conductors may be molded into

a single body member formed with openings at the respective female contact elements.

In employing the plug receptacle device, the prongs 11 and 12 may be inserted into a conventional wall receptacle, whereby said prongs are connected to a power line, as shown in Figure 5. The load, which may be a lamp or other appliance is designated at 29. Said load is provided with a conventional line cord having a two-prong plug which is plugged into the device at female contact elements 17 and 19. Designated at 30' is a single pole double throw switch having a three wire line cord provided with a plug 30. This plug is inserted in the device at the female contact elements at one lateral side of the device, thereby engaging bars 18, 16 and 14 to establish the circuit shown at the left side of Figure 5. From Figure 5 it will be seen that the pole of switch 30' may be employed to electrically connect female element 18 to either contact bar 14, whereby the load 29 is energized, or to bar 16, whereby the load is shunted and deenergized. The load may be in one part of a room and the switch 30' may be in another part of the room, thereby affording remote control of the load.

If the load is instead connected to female contact elements 19 and 20, as shown in dotted view at 29' in Figure 5, and an additional single pole-double throw switch 31 is employed, connected to the side of the receptacle device opposite to switch 30' in the manner shown at the right side of Figure 5, the load 29' may be controlled from either switch 30' or switch 31.

It will be noted that in accordance with the wiring scheme of Figure 5, the pole of switch 30' is connected to female contact element 18, one stationary contact thereof is connected to bar 16, and the other stationary contact thereof is connected to bar 14. Similarly the pole of switch 31 is connected to female element 21 and the stationary contacts thereof are respectively connected to bars 16 and 14. When only one switch is employed, the connection to bar 16 may be omitted and the load will be energized from female contact elements 17 and 19, as shown in full line view in Figure 5. To use two switches, the load must be disconnected from female contact 17 and connected across contacts 19 and 20, as shown in dotted view.

The device may be employed as an ordinary cube tap by engaging conventional two-prong plugs with the respective pairs of female contact elements at the opposite ends of the bars 14 and 16.

The plug receptacle may be inserted into a lamp socket such as shown at 32 in Figure 9, instead of a convenience outlet by engaging on prongs 11 and 12 a conventional screw type plug 33, which enables the device to be then screwed into any standard lamp socket. A female lamp socket 34 may be electrically connected to either prongs 17 and 19 or prongs 17 and 20, enabling a lamp 35 screwed therein to be remotely controlled from either one or two points, as above described.

Instead of employing the standard prong spacing of prongs 11 and 12 shown in Figures 1 and 6, the prongs may be spaced apart so as to engage the outer end prong receptacles of a double socket such as shown at 36 in Figure 8. The prongs, shown at 11' and 12', are electrically connected to the respective conductors 14 and 16 in the same manner as described in connection with Figure 1, but are mechanically connected to these conductors to provide sufficient spacing so as to engage in the outer prong receptacles

of the double socket 36. The arrangement of Figure 8 provides a centered position of the plug-in receptacle device with respect to the double socket.

Figure 7 illustrates a modified form of the plug receptacle device which provides control of a load 37 from two different locations by means of the respective single-pole double-throw switches 38 and 39. In the modified form of the device shown in Figure 7, the numerals 41 and 42 designate metallic prong conductors of standard size and spacing. Prong 41 is connected by a bridging strap conductor 43 to a female contact element 44. Prong 42 is connected by a similar bridging strap conductor 45 to a second female contact element 46 parallel to element 44. Designated at 47 and 48 are the spaced transverse conductor bars which underlie but are insulated from the strap conductors 43 and 45. Secured to prong 41 and extending at right angles thereto is a female contact element 49, said element 49 being parallel to and spaced from the left end portion of bar 47, as viewed in Figure 7. Designated at 50 is a female contact element parallel and spaced 25 to the right of the female contact element 46, as viewed in Figure 7. Secured to element 50 and extending at right angles thereto is the female contact element 51, which is parallel to and spaced below the right end portion of bar 48, as viewed in Figure 7. The conductor elements are mounted in an insulating body shown in dotted view at 52.

Where no remote control of the load is desired, it may be connected directly to the female contact elements 44 and 46. However, if remote control of the load is desired, it is connected to the female contact elements 46 and 50, as shown in Figure 7, and the respective switches 38 and 39 are connected by suitable plugs and cords to the respective left and right sides of the device. From Figure 7 it will be seen that the pole of switch 38 is connected to female contact element 49 and the stationary contacts thereof are connected respectively to bars 47 and 48. The pole of switch 45 39 is connected to female contact element 51 and the stationary contacts of switch 39 are connected to the bars 47 and 48. It will be seen from Figure 7 that one terminal of the load is connected through contact element 46, strap 45 and prong 42 to one of the power supply wires; the other power supply line wire may be connected to either conductor 47 or 48 by means of the movable pole of switch 38. The remaining terminal of the load 37 is connected through contact element 50, and contact element 51 to the pole of switch 39. The pole of switch 39 may be moved into electrical connection with either conductor 47 or 48. With switch 38 in a given position, the load may therefore be controlled by switch 39; conversely, with switch 39 in a given position, said load may be controlled by switch 38.

While certain specific embodiments of plug-in receptacles for providing remote control of an electrical load have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A plug-in receptacle device of the character described comprising an insulating body member, a pair of parallel conductor bars secured in said body member, a pair of spaced prongs secured

respectively to said conductor bars and projecting outwardly from one face of the body member, a first female contact element secured to one of the conductor bars within the body member and extending toward the opposite face of the body member, a second female contact element located within the body member parallel to said first female contact element, a third female contact element secured within the body member to said second female contact element and extending toward a lateral face of the body member and being parallel to an end portion of said one conductor bar, a fourth female contact element located within the body member parallel to said first female contact element, a fifth female contact element secured within the body member to said fourth contact element and extending toward a lateral face of the body member and being parallel to another end portion of said one conductor bar, the respective ends of the conductor bars being formed to define female contact elements and the body member being recessed adjacent the respective female contact elements to define apertures for the insertion of plugs, said conductor bars, prongs and first, second, third, fourth and fifth female contact elements being formed of flat bar stock and their axes lying substantially in the same plane.

2. A plug-in receptacle device of the character described comprising an insulating body member, a pair of parallel conductor bars secured in said body member and extending substantially from one lateral face of the body member to the other, a pair of spaced prongs secured respectively to said conductor bars and projecting outwardly from the rear face of the body member, a first female contact element secured to one of the conductor bars within the body member and extending adjacent the front face thereof, a second female contact element located within the body member parallel to said first female contact element, a third female contact element secured within the body member to said second female element and extending adjacent one lateral face of said body member and extending parallel to one end portion of said one conductor bar but lying in a plane at right angles thereto, a fourth female contact element located within the body member extending parallel to and spaced from the first female contact element opposite to the second female contact element but lying in a plane at right angles to said first female contact element, and a fifth female contact element secured within the body member to said fourth female contact element extending adjacent the remaining lateral face of the body member and

extending parallel to the adjacent end portion of said one conductor bar but lying in a plane at right angles thereto, the ends of the conductor bars being formed to define female contact elements and the body member being recessed adjacent to the respective female contact elements to define apertures for the admission of prongs, said conductor bars, prongs and first, second, third, fourth and fifth female contact elements being formed of flat bar stock and their axes lying substantially in the same plane, the planes of said spaced prongs being perpendicular to the planes of said conductor bars.

3. A plug-in receptacle device of the character described comprising a pair of parallel conductor bars, a pair of parallel prongs connected respectively to the conductor bars and projecting respectively at right angles thereto, a first female contact bar projecting from one of the conductor bars at right angles thereto in a direction opposite to that of said prongs, a first set of female contact bars spaced on opposite sides of the first female contact bar and extending parallel thereto, and a second set of female contact bars secured respectively to the inner ends of the first set of female contact bars and extending parallel and adjacent to the end portions of said one conductor bar, the respective ends of the conductor bars being formed to define female contact elements, said conductor bars, prongs and first and second sets of female contact bars being formed of flat bar stock and their axes lying substantially in the same plane, the planes of said spaced prongs being perpendicular to the planes of said conductor bars, at least one of said first set of female contact bars lying in a plane at right angles to the planes of the other of said first set of female contact bars, and said second set of female contact bars lying in a plane at right angles to the plane of said one conductor bar.
